UNITED STATES PATENT OFFICE

1,957,687

TOY WITH SPARK PRODUCING DEVICE

Carl Arnold, Nuremberg, Germany

Application March 30, 1933, Serial No. 663,573
In Germany January 25, 1933

1 Claim. (Cl. 46-48)

It is known in connection with toy locomotives to visibly project beams of sparks from the funnel. According to the invention these beams of sparks are at the same time utilized for illuminating the boiler, cab, cabins and the like in all kinds of toys.

An embodiment of the invention is illustrated by way of example in longitudinal section in the only figure of the accompanying drawing.

In the interior, for example, of a locomotive *a* a driving mechanism *b* is mounted which actuates a spark producing device from which the spark beams are visibly projected through the funnel. According to the invention these beams of sparks are utilized at the same time for illuminating the boiler, cab, smoke box cover, cabins and the like of toy locomotives, ships and similar toys. For this purpose the so-called smoke box cover on the front end of the locomotive boiler consists of a coloured gelatine plate

d. The cab *f* is likewise shut off from the boiler by a gelatine plate *g*. To enable the cab to be perfectly lighted, a second cerium stone mounted in a separate stone holder *h* suspended in the boiler brushes against the friction wheel. The above described arrangement adds to the interest of the toy as thereby the toy is completely lighted by simple means.

I claim:

A toy with spark producing device, comprising in combination with the spark producing device, a case simulating a boiler accommodating said device, a smoke box cover on the front of the boiler, and a cab at the rear end of the boiler, coloured transparent gelatine plates in said smoke box cover and said cab, through which the sparks produced by said device are visible.

CARL ARNOLD.
